FRANK L. O. WADSWORTH, OF ALLEGHENY, PENNSYLVANIA, ASSIGNOR
TO PRESSED PRISM PLATE GLASS COMPANY, OF MORGANTOWN, WEST
VIRGINIA, A CORPORATION OF WEST VIRGINIA.

APPARATUS FOR GRINDING OR POLISHING GLASS.

SPECIFICATION forming part of Letters Patent No. 792,564, dated June 13, 1905.

Application filed October 6, 1903. Serial No. 175,966.

To all whom it may concern:

Be it known that I, FRANK L. O. WADSWORTH, of Allegheny, Allegheny county, Pennsylvania, have invented a new and useful Apparatus for Grinding or Polishing Glass, of which the following is a full, clear, and exact description, reference being had to the accompanying drawings, forming part of this specification, in which—

10 Figure 1 is a vertical central section showing one form of apparatus embodying my invention, and Fig. 2 is a partial top plan view of the same.

15 My invention relates to the grinding or polishing of glass plates or sheets, and is designed to provide an effective apparatus by which both sides of the glass are ground or polished simultaneously.

20 A further object of the invention is to provide mechanism for acting upon both faces of the glass in such a manner that the frictional forces tending to move the glass in its own plane are substantially equal and opposite on its opposite sides in every part of the glass.

25 In the drawings the upper disks 47 and the lower disks 48 are provided with hollow shafts extending through stationary bearings in plates 49 and 50. The hollow shafts 51 for the upper disk are preferably provided with 30 collars 52, carried at the inner ends of the counterweighted levers 53. The weights on these levers partially counterweight the disks, which would otherwise bear too heavily on the upper face of the sheet. I have shown 35 the rings 52 as having ball-races containing balls engaged by hubs on the sprocket-wheels 54, secured to the upper ends of the hollow shafts. The upper disks are simultaneously driven in the same direction by a sprocket-chain 55, which extends around the sprocket-wheels 54, as shown in Fig. 2, and around an idler-sprocket 56 and a driving-sprocket 57. The sprocket-wheels 58 for the lower shafts are provided with a sprocket-chain extending 40 around a driving sprocket 59, secured to a counter-shaft 60, having gearing connec-

tion 61 at its top with the shaft of the sprocket-wheel 57. The upper and lower disks are thus rotated in opposite directions. The glass sheet 62 is held between removable separate 50 plates 63, which are bolted to an outer frame 64, entirely surrounding the sheet and which rests upon a surrounding stationary bed-plate 65. The frame 64 may be moved in any suitable manner, and I have shown it as adapted 55 to be moved by hand, it being recessed on the under face to receive ball 66, resting on the bed-plate. This frame does not in any way support the glass, which rests of its own weight on the lower disks. The upper portions of the hubs of the sprocket-wheels 54 are preferably formed in funnel shape to receive the abrading material fed through spouts 67 from a longitudinal receptacle or hopper 68. In this horizontal form the frictional force exerted on the lower face of the 60 glass would be greater than that upon the upper face, owing to the weight of the sheets, and to make these forces substantially equal 65 I may provide different forms of mechanism. 70 It may be accomplished by driving the lower disks at a lower rate of speed than the upper disks. In the form shown I accomplish this result by connecting the hollow shafts of the lower disks with the feed-box 69, to which 75 leads a pressure-supply pipe 70. The abrading material for the lower disks is mixed with a liquid, such as water, and is forced in under pressure, this pressure being graduated so that its lifting action on the sheet of glass will 80 cause it to substantially float between the upper and lower disks, so that the frictional forces are substantially alike on both faces. To assist in this action, I may use an Archimedean screw 71 in the cylindrical feed-box 85 69 and having its shaft 72 extending through a stuffing-box in the end and driven through a suitable connection. In using this form the upper and lower disks are driven in opposite directions, and the abrading material feeds 90 through the upper shafts by gravity, while it is forced upwardly under pressure through

the hollow shafts of the lower bed. The frictional forces are thus substantially equalized, and the plate-frame may be moved by the attendant, or driving, mechanism used to cause 5 an equal action on its different portions.

The advantages of my invention result from the simultaneous grinding of both sides of the glass without danger of breaking or cracking thereof. The abrading action is equalized on all parts and the frictional forces are substantially neutralized. The delay of embedding the glass is avoided and the temperature of the glass on both sides is substantially the same, so that the danger of breakage owing 10 to this difference of temperature is obviated.

Many variations may be made in the form and arrangement of the apparatus without departing from my invention, since I consider 20 myself first to act upon both faces and at the same time substantially equalize the frictional forces.

I claim--

1. In glass grinding or polishing apparatus 25 a pair of disks lying in approximately horizontal planes, mechanism for driving the disks in opposite directions, and means for holding a glass sheet between the disks; substantially as described.
2. In glass grinding or polishing apparatus 30 a pair of disks lying in approximately horizontal planes, mechanism for driving the disks in opposite directions, means for holding a glass sheet between the disks, and means for

varying the pressure of the upper disk on the 35 glass; substantially as described.

3. In glass grinding or polishing apparatus a pair of disks lying in approximately horizontal planes, mechanism for driving the disks in opposite directions, means for holding a 40 glass sheet between the disks, and means for forcing an abrasive mixture upwardly against the lower face of the glass sheet; substantially as described.

4. In glass grinding or polishing apparatus 45 a pair of disks lying in approximately horizontal planes, mechanism for driving the disks in opposite directions, and means for holding a glass sheet between the disks, said means being arranged to allow the sheet to be moved 50 in different directions; substantially as described.

5. In glass grinding or polishing apparatus a plurality of pairs of disks arranged in substantially horizontal planes and opposing each 55 other, mechanism for driving the disks in opposite directions, the lower disks being arranged to receive a glass sheet resting thereon, and means for feeding the abrading material to the upper and lower faces of the plate; 60 substantially as described.

In testimony whereof I have hereunto set my hand.

FRANK L. O. WADSWORTH.
